Primary Examiner—Stella Reid*Assistant Examiner*—Shanda C. Hill(74) *Attorney, Agent, or Firm*—McKee, Voorhees & Sease, P.L.C.**CLAIM**

The ornamental design for an ice compartment for a refrigerator fresh food compartment, substantially as shown and described.

DESCRIPTION

FIG. 1 is a front elevation view of an ice compartment for a refrigerator fresh food compartment showing our new design;

FIG. 2 is a right elevation view thereof;

FIG. 3 is a bottom plan view thereof;

FIG. 4 is a front elevation view of an alternative embodiment of the ice compartment for a refrigerator fresh food compartment of FIG. 1;

FIG. 5 is a left elevation view thereof; and,

FIG. 6 is a bottom plan view thereof.

The broken lines shown in the drawing disclosure are for illustrative purposes only and form no part of the claimed design.
